UNITED STATES PATENT OFFICE.

WILLIAM A. STOFER, OF FOXBURG, PENNSYLVANIA.

CONNECTION FOR RAILWAY-RAILS.

SPECIFICATION forming part of Letters Patent No. 466,634, dated January 5, 1892.

Application filed February 26, 1890. Serial No. 341,869. (No model.)

To all whom it may concern:

Be it known that I, WILLIAM A. STOFER, a citizen of the United States, and a resident of Foxburg, in the county of Clarion and State 5 of Pennsylvania, have invented certain new and useful Improvements in Connections for Railway-Rails; and I do declare the following to be a full, clear, and exact description of the invention, such as will enable others skilled 10 in the art to which it appertains to make and use the same, reference being had to the accompanying drawings, and to letters of reference marked thereon, which form a part of this specification.

15 Figure 1 of the drawings is a perspective view. Fig. 2 is a view of the bolt. Figs. 3 and 4 are views of the keys.

This invention relates to certain improvements in fastenings for railway-rails; and it 20 consists of the novel construction and combination of parts, as will appear from the following description and illustration.

In the drawings, A A represent the adjoining rails of a section of a railway, and B an 25 angle-plate, which is arranged to break joints with said rails.

C C are bolts passed through apertures in the rails A and angle-plate B, and each of 30 which has a transverse aperture a near one end.

D D are split keys or pins, which may be slightly tapered, and which are passed through coincident holes or apertures of the rails A and angle-plate B. The keys are each provided with an offset portion or shoulder b near 35 its head.

In operation the bolts are passed through registering holes or apertures of the rails and angle-iron, and the keys or pins are driven 40 into the slots or apertures of said bolts. By

the insertion of a suitable tool or implement into the split ends of the keys or pins the prongs formed by thus splitting the keys are caused to diverge, and in that manner lock the keys in said bolts, and consequently prevent the accidental displacement or jarring out of place of the bolts. 45

In the modification, as disclosed in Fig. 4, I have provided a key D', which is also slightly tapered and split at its unheaded end, the 50 prongs D, however, in this case being flexed or bent outward, as at d, from each other and converged at their outer free ends. The outward flexed or bent portions of the prongs of this key as it is driven into the opening of the 55 bolt will be compressed or brought nearly parallel, elongating said prongs, and after the key is driven home they will resume their original position, and thus automatically lock the key in place in the bolt. In either case 60 the key is removed by striking against its shoulder or offset at or near the head end with a suitable implement.

Having described this invention, what I claim, and desire to secure by Letters Patent, 65 is—

The herein-described key for locking bolts in position, comprising the flat tapering shank portion having an offset or head at one end, its opposite end being split longitudinally, 70 said split portions or prongs being flexed or bent outward from each other at their intermediate portions and converged at their outer free ends, substantially as specified.

In testimony whereof I affix my signature in 75 presence of two witnesses.

W. A. STOFER.
